UNITED STATES PATENT OFFICE.

THOMAS L. RYAN AND OVERTON SACKSTEDER, JR., OF MUNCIE, INDIANA, ASSIGNEES
TO RETHERFORD BROTHERS COMPANY, OF MUNCIE, INDIANA, A CORPORATION.

SHADE-HOLDER.

1,333,736.

Specification of Letters Patent. Patented Mar. 16, 1920.

Application filed July 29, 1919. Serial No. 314,098.

To all whom it may concern:

Be it known that we, THOMAS L. RYAN and OVERTON SACKSTEDER, Jr., citizens of the United States, residing at Muncie, in the 5 county of Delaware and State of Indiana, have invented certain new and useful Improvements in Shade-Holders, of which the following is a specification.

This invention relates to improvements in 10 shade-holders or supports for electric lighting fixtures, and has reference especially to a holder that is applicable to portable lamps of that class consisting of a base or column, above which is supported a shade, and beneath which shade is disposed the electric bulb.

An object of this invention is to provide 20 a holder which is easy to install and is capable of retaining the shade securely and in correctly aligned position. Further purposes of the invention are to provide a holder upon which the shade may be easily adjusted to correct position and then easily secured, and which holder will be light in 25 weight, neat in appearance, and economical of manufacture.

The objects of our invention are accomplished by, and the invention is embodied in the new construction, combination and arrangement of parts shown in the annexed drawings, and described in the following specification. The invention is defined in the appended claims.

The several parts of the invention are 35 identified by suitable characters of reference applied thereto in the several views in the drawings, in which:

Figure 1 is a side view of a portable lamp complete and which comprises in its construction, one of our improved holders, the 40 glass shade being shown in section.

Fig. 2 is a side view, and Fig. 3 is an end view of the holder frame.

Fig. 4 is a top plan view of the holder 45 frame.

Fig. 5 is a top plan view of the retaining cap.

Fig. 6 is a top plan view taken on the line 6-6 in Fig. 2.

The body portion, or frame of our improved holder, is harp shaped as shown in 50 Fig. 1 and Fig. 2. The side arms A and A spring from the flat circular shaped bottom plate B and extend upwardly practically 55 parallel, thence flare outwardly and then

are turned toward each other diagonally whence they meet and terminate in a central projection or stem C.

At points spaced equidistant from the stem C are transverse cross-arms D and D.

The horizontal faces D¹ and D¹ of these cross arms are arcuate and of curvature of slightly greater degree than the degree of a curve struck from a center on the plane of said cross arms as shown in Fig. 4. The 65 purpose of this feature will be presently referred to.

A concave cap E, light in weight, and made preferably of stamped construction, has a central hole E¹ which permits the cap 70 to be disposed at position with its edges at registration with the top surface of the shade 2. We have shown in this illustration of our invention, the shade 2 made of glass; it is obvious that our invention is of 75 equal utility in the use of shades made of metal or other material having such form that the under surface of its upper portion may have bearing on the cross arms.

A metal knob F, having a central threaded 80 bore, when screwed down on the stem C makes contact against the cap E and forces it to engagement with the top surface of the shade. There being a slight clearance space 85 3 between the inner surface of the cap, and the outer surface of the rim edge of the glass, it is practicable to adjust the shade in any direction necessary that the bottom line of the shade may be perfectly at a right angle to the center line of the holder, and 90 therefore of the fixture column 1.

This adjustment feature is essential for the reason that shades made of glass are not perfect in contour. That is to say,— 95 although the glass may be cast in perfectly machined molds, the glass shade itself, after being cooled and annealed, is not uniformly perfect; a large proportion of glass shades being "out of round."

To meet this physical defect in the glass 100 shades, the degree of curvature, horizontally, of the cross arms, is slightly greater than if of a degree of curvature struck from a point central of these cross arms. The same thing is true of the degree of 105 curvature of the vertical curve D². This curve is of such degree that the under side of the shade has bearing only on a portion of the surface of the cross arm. It is apparent that by this arrangement the under 110

side of the shade is engaged by the end portions and by the horizontal portion of the cross arms intermediate the top and bottom edges. With the construction and combination with the side arms A and A₁ of the cross arms D and D as shown and described, there may be retained practicably by this holder device, glass shades of the standard commercial type; and the shades will be retained securely and accurately, even though the internal contour of the shade may be, as above referred to, technically imperfect. Moreover, the shade so supported cannot become loose or "wabbly" and the lamp as an entirety may be shifted and moved about without risk of damage to the shade.

It will be understood that the above detailed description as to the curvature horizontally and vertically of the cross arms, is not intended as a limitation of the scope of this invention; it being apparent that cross arms of angular formation would perform the same function, though not quite so desirably, as that performed by the cross arms formed as above described. Also it might be desirable, if necessary, to construct the cross arms of a predetermined contour to precisely register with the contour of the under side of the metal or glass shade to be used. Another advantage of the invention is that the securing of the holder to the lamp base is very simple; the bottom plate B being seated on the faced top of the base column 1; the electric socket 4 is screwed down on the threaded nipple 5 that is passed through the hole B¹, and the holder frame is thus tightened securely at accurately aligned position.

What we claim as our invention, and desire to secure by Letters Patent is:—

1. In a shade holder, an integral harp shaped member having the arched upper ends of the sides thereof formed at their juncture with an integral stem, a cross arm

on each of said arched parts extending on opposite sides thereof and disposed at spaced points below the stem, and a retaining member secured to the stem.

2. In a shade holder, a harp-shaped member, a cross arm on each of the arched upper ends of the sides of the member located at points spaced below the top of the member, whereby the weight of the shade is borne directly by the arched upper ends of the member, and means to secure the shade to the member.

3. In a shade holder, an integral harp shaped member having the arched upper ends of the sides thereof formed at their juncture with an integral stem, a cross arm on each of said arched parts extending on opposite sides thereof and disposed at spaced points below the stem, and said cross arms having dished outer faces and being relatively thick and wide and of approximate rectangular formation, and a retaining member secured to the stem.

4. In a shade holder, a harp-shaped member, a shade bearing element on each of the arched upper ends of the sides of the member whereby the weight of the shade will be directly borne by said arched upper ends of the member, said members extending oppositely beyond the respective opposite sides of the member, and a retaining element for the shade.

5. In a shade holder, an open frame having an arched top part, a relatively wide and long part borne by each of the sides of the arched top part and extending outwardly beyond the opposite side faces of said sides, and a retaining element for the shade borne by the frame.

In testimony whereof we affix our signatures.

THOMAS L. RYAN.
OVERTON SACKSTEDER, JR.
